(57) **CLAIM**

The ornamental design for a portable communication device, substantially as shown and described.

DESCRIPTION

This application is related to the applications titled Pocket Clip for Portable Communication and Clip for Portable Communications Device being filed concurrently.

FIG. 1 is a left front perspective view of the portable communication device showing our new design;

FIG. 2 is a rear view of the portable communication device;

FIG. 3 is a front view of the portable communication device;

FIG. 4 is a top view of the portable communication device; and,

FIG. 6 is a bottom view of the portable communication device.

The broken lines in FIG. 2 show elements of the portable communication device that form no part of the claimed design.
